FISHING REEL

Walter Willman, St. Petersburg, Fla., assignor to
 James Heddon's Sons, Dowagiac, Mich., a corporation of Michigan

Application April 18, 1946, Serial No. 663,049

5 Claims. (Cl. 242—84.1)

1

This invention is concerned with a reel having provision for facilitating an adjustment of certain parts coaxial with the operating handle whereby to compensate for wear at that point. In this way I eliminate play and noise whenever it develops. Furthermore the present reel embodies a novel support for the bearing plate whereon is mounted the stud about which the operating handle is rotated. This support is adequate to maintain the stud in normal relation to the bearing plate even though it be subjected to severe lateral stresses during usage of the reel over a prolonged period of service. In addition, my present reel embodies a novel construction whereby the take-up and supporting parts are made accessible, wherever occasion may arise to perform any work upon them or effect any assembly thereof.

These various objects and advantages which are derivable from my invention will more fully be set forth in the succeeding description, wherein reference is made to a suggestive embodiment of my invention in the manner following:

Fig. 1 is a perspective view of the reel, looking toward the head end thereof;

Fig. 2 is a central longitudinal section therethrough, taken on line 2—2 of Fig. 1;

Fig. 3 is a transverse section through the reel, taken on line 3—3 of Fig. 2;

Fig. 4 is an enlarged detail in section, taken on line 4—4 of Fig. 3;

Fig. 5 is a view in perspective, partly broken away, showing the inner and outer head plates, together with the interconnecting means therefor; and

Fig. 6 is a detail in section, taken on line 6—6 of Fig. 3.

The principal operating units of the present reel may be of any conventional type, either with or without a level winding feature. It will be understood, therefore, that the present invention is not directed to specific details in the arrangement of the gearing, or such accessory features as a click, drag, or level winding device.

For purposes of illustration, I have chosen a relatively simple type of reel comprising the usual reel clip plate 18 which is carried by a lower pillar 11 which in conjunction with a side pillar 12 (one or more) and a top pillar 13 serves to connect the tail plate 14 with an inner head plate 15. The pillars at their head ends are inwardly shouldered to provide reduced necks 17 which are fitted closely within holes formed through the head plate 15, the ends of the necks terminating substantially flush with the outer face of the head plate.

Extending axially into each pillar neck from its outer end is a threaded socket wherein may engage a threaded stem 18 which extends axially from the inner end of a spacer post 19 of increased diameter, this post being shown as formed with a transverse hole 20, through which may be entered a small implement to apply a rotary force thereto. When the post is turned to advance its stem within the pillar socket, the inner end of the post will be brought home against the outer face of the head plate 15 whereby to become fixed rigidly with respect thereto. The outer end of each spacer post is shouldered inwardly to provide a reduced neck 21 which may be closely fitted within a registering hole in an outer head plate 22. The end of this neck terminates substantially flush with the outer face of the outer head plate, and a threaded shank 23 is adapted to engage within a threaded socket formed in the outer end of the spacer post. This shank is part of a screw having a slotted head 24 which is adapted to bear against and engage with the outer face of the outer head plate 22, whereby to hold this head firmly against the shoulders of the spacer posts of which three is the preferred number, one being fitted to each pillar as an extension thereof.

The construction thus far described provides a reel framework having at one end two spaced heads, one fixed with respect to the other, the outer head being removable from the spacer posts, and the latter being removable from the pillars, whenever disassembly is to be undertaken. A peripheral shoulder 25 may be formed around the outer head plate, and screw threads around the periphery of the inner head plate, so that a cap 26 having an inturned flange 27 may be fitted around both plates, the flange being adapted to seat itself against the shoulder 25. Screw threads 28 are formed internally of the cap for engagement with the peripheral threads of the inner head plate whereby to cause the cap, when rotated, to advance axially with pressure against the outer head plate where it normally remains during use of the reel. The protection thus afforded by the cap to the operating parts between the two head plates is a feature that is more fully dealt with in my Patent No. 2,391,935 of January 1, 1946.

The inner and outer head plates, in conjunction with the tail plate, support bearings 30 and 31 for the spindle of a spool 32. These bearings are of any conventional type, so need not be described in detail. The inner and outer head plates afford mountings for a suitable train of gearing *g* which transmits rotation from a handle 33 to the spindle

34 of the spool in the usual manner. It will be understood that the details of the bearings and gear train may be varied or modified along conventional lines, and that the features of the present invention are concerned rather with means presently to be described than to the details of construction and arrangement of the operating parts themselves.

The handle is provided intermediately of its ends with an opening which is non-round, such as a square, to receive a similarly shaped peripheral portion 35 which is formed near the outer end of a hub 36 which is extended axially from a pinion 37 at its inner end. The hub-pinion unit is mounted for rotation upon a fixed stud 38 whose inner end is inwardly shouldered to provide a reduced neck 39 which is extended through an opening near one edge of a bearing plate 40, the end of the neck being upset or otherwise formed to engage with the inner face of the bearing plate whereby to secure the stud fixedly and immovably thereto and in normal relation therewith. At its outer end the hub 36 is externally threaded at 41 for engagement by a cap nut 42 whereby the handle may be locked operatively in place. The bearing plate 40, here shown as circular, is peripherally shouldered at 43. A large opening which is provided in the inner head plate 15, eccentrically thereof, is adapted to receive the bearing plate whose shoulder may rest against the outer face thereof to provide a closure therefor. To secure the bearing plate fixedly in place, I employ three screws whose heads 44 engage with the outer face of the outer head plate 22, the threaded shanks 45 of these screws passing through openings 46 in the head plate to engage with the bearing plate which is maintained a fixed distance apart from the outer head plate by spacer sleeves 47 which surround the screw shanks. In the present construction the bearing plate, although fitting over the inner head plate opening, is carried by the outer head plate 22 through the medium of the three-point support just described.

Surrounding the hub 36 in spaced relation thereto is a bushing 50 which is externally threaded for cooperative engagement with a nut 51 and a lock washer 52 adjacent thereto. This nut which is fixedly seated within an opening through the outer head plate 22, is provided with a shoulder 53 which abuts the outer face of this head plate and at its inner end with a head 54 in flush engagement with the inner face of the same plate. The bushing may be provided at its outer end with an out-turned flange 55 against which the handle may bear lightly in response to tightening of the cap nut 42. In the assembly just described, the bushing is extended inwardly to contact the transverse wall of a collar 56 to the outer side thereof. The bushing may be rotatively adjusted to present its inner end closely adjacent the collar 56 so as to provide an end thrust bearing therefor. Closely surrounding this collar and secured fast thereto is a ring gear 57 forming a component of the train of gears whereby the spool is operated from the handle.

In use of a reel, the handle-driven gear including its associated hub and parts engaged thereby, is subjected to hard treatment with the result that wear, play, and noise tend to develop. It is ordinarily impossible to rectify such a condition short of replacing one or more of the worn parts. In the present reel mechanism, I am able to compensate for wear by the simple expedient of loosening the lock nut 52, then rotatively ad-

vancing the bushing through the slight distance necessary for the purpose. The hub and its collar may be produced from whatever material is best suited for free running on its axial and end bearings, whereas the gear 57 which is carried thereby may, if desired, be formed from a different material, although, optionally, it may be formed integral therewith. The presence of the bushing acts also as a protecting cover for the gears to the inside thereof. By taking advantage of the provision for wear compensation above referred to, the reel can be maintained in a noiseless free-running condition through a prolonged period of heavy service.

15 The bearing plate 40, as already noted, may be fitted closely against the inner head plate 15 in such a position as to constitute a complete closure for the large opening which it covers. This plate is carried by the outer head plate 22 which, by means of the cap 26, is maintained tightly in a position which is accurately spaced by the posts 19 from the inner head plate 15. As shown, the support extending from the outer head plate 22 to the bearing plate 40 is at three spaced points defining a figure which is triangular. This is both important and advantageous because such a support is sufficiently steady and balanced to adequately withstand the lateral stresses that are set up as the result of the off-center location of the stud 38 about whose axis the handle is required to rotate. In use, therefore, the multi-point support for the bearing plate will afford a base for the stud such that the one will be maintained always in normal relation to the other. As a consequence, there will be less noise from, and wear of, the gears over a prolonged period of service.

20 The extension posts serve also as spacers whereby the distance remains fixed between the inner and outer head plates. It is possible by use of an appropriate implement to advance each post so tightly in its threaded engagement with the associated pillar as to prevent normally any separation therebetween. This is of advantage because if the outer head plate is to be removed 25 loosening of the holding screws 23 will not affect the extension posts which remain locked to their pillars.

I claim:

1. In a fishing reel, the combination of a tail plate at one end and at the other end inner and outer head plates defining a chamber therebetween, a plurality of sectional means spaced from each other and each extending in a straight line from end to end and consisting of a pillar and a post detachably and adjustably connected with an end of the pillar and connecting the tail plate with the inner head plate and the inner head plate with the outer head plate, the inner head plate being clamped between the pillar and the post and the post providing the connection between the inner head plate and the outer head plate, there being in the inner head plate a circular opening, a bearing plate having a peripheral shoulder overlapping the marginal edge of the circular opening of the inner head plate to provide a closure therefor, means interconnecting the bearing plate and outer head plate at a plurality of spaced points in normally inseparable relation whereby the bearing plate is supported by the outer head plate and removable therewith as a unit from the inner head plate when the inner head plate is disengaged from the tail plate, a spool mounted for rotation between the tail plate and the bearing plate, a stud mounted on

the bearing plate and extended outwardly therefrom opposite an opening in the outer head plate through which the stud projects, a gear mechanism within the chamber including a gear rotatably mounted upon the stud and having driving connection with the spool; a bearing through which the gear carried by the stud is journaled for rotation, said bearing being carried by the outer head plate and longitudinally adjustable and having abutting engagement with the gear upon the stud, and an operating handle in connection with the gear mechanism mounted for rotation coaxially with the stud.

2. In a fishing reel, the combination of a tail plate at one end and at the other end an outer head plate, spaced means interconnecting the tail and outer head plates at points adjacent their peripheries, an inner head plate fixedly supported by the interconnecting means at a point relatively close to the outer head plate and defining a chamber therebetween, there being in the inner head plate an opening inwardly of the interconnecting supporting means, a bearing plate adapted to fit over the opening of the head plate to provide a closure therefor, a three-point normally inseparable connection between the bearing plate and the outer head plate whereby the former is supported by the latter in unitary relation therewith, a spool mounted for rotation between the tail plate and the bearing plate, a stud mounted on the bearing plate and extended normally therefrom opposite an opening in the outer head plate through which the stud projects, and operating means for the spool comprising a handle mounted for rotation coaxially with the stud.

3. In a fishing reel, the combination of a tail plate at one end and at the other end inner and outer head plates defining a chamber therebetween, a plurality of pillars interconnecting the tail plate and inner head plate, a plurality of posts, one coaxial with each pillar, extending between the inner and outer head plates in engagement with their confronting faces to serve as spacers therebetween, means removably connecting each post with one pillar and with the outer head plate, a bearing plate supported by the outer head plate providing a mounting for a train of gear mechanism within the chamber, a stud associated with the gear train supported at one end by the bearing plate and extended outwardly therefrom normally thereof through an opening in the outer head plate, and a handle mounted for rotation coaxially with the stud.

4. In a fishing reel, the combination of a tail plate at one end and at the other end inner and outer head plates defining a chamber therebetween, a plurality of parallel spaced means, each comprising a pair of axially aligned separably joined sections, interconnecting the tail plate with the inner head plate and the inner head plate with the outer head plate, a bearing plate carried by the outer head plate in unitary rela-

tion therewith providing a mounting for a train of gear mechanism within the chamber, a stud associated with the gear train supported at one end by the bearing plate and extended outwardly therefrom normally thereof through an opening in the outer head plate, and a handle mounted for rotation coaxially with the stud.

5. In a fishing reel the combination of a frame comprising a tail plate at one end and at the other end a removable head plate, posts removably associated with the reel frame and detachably connected with the head plate to provide a seat therefor in a predetermined spaced relation to the reel frame, a bearing plate, other posts spaced radially inwardly from the first posts and detachably engaged with the head plate and the bearing plate and holding the bearing plate in predetermined spaced relation to the head plate and permitting removal of the bearing plate with the head plate after separation of the head plate from the reel frame, a spool mounted for rotation between the tail plate and the bearing plate, operating means for driving the spool comprising a stud mounted on the bearing plate and extended outwardly therefrom opposite an opening in the head plate and through which the stud projects, a hub mounted for rotation on the stud having a wall formed with a portion transversely extended therefrom at a point remote from its outer end, a nut fixedly carried by the head plate, a bushing threaded through the nut and adjustably supported thereby in surrounding relation with the hub and having a portion projecting outwardly from the nut, the inner end of the bushing contacting the transversely extending portion of the transverse wall of the hub to provide an end thrust bearing therefor, means for locking the bushing in a selected position of longitudinal adjustment relative to the nut, and a cap in screw-threaded connection with the reel frame and in overlapping engagement with marginal portions of the head plate for securing the latter in place and serving also as a marginal closure for space between the bearing plate and the head plate.
